UNITED STATES PATENT OFFICE.

JOSEPH A. HAMMER, OF GALESVILLE, WISCONSIN.

HANGER.

1,117,842.

Specification of Letters Patent. Patented Nov. 17, 1914.

Application filed December 27, 1913. Serial No. 809,039.

To all whom it may concern:

Be it known that I, JOSEPH A. HAMMER, a citizen of the United States, residing at Galesville, in the county of Trempealeau 5 and State of Wisconsin, have invented new and useful Improvements in Hangers, of which the following is a specification.

This invention relates to hangers or supports for wall calendars or like articles, the 10 object of the invention being to provide a hanger or support forming a permanent fixture of the calendar, whereby such article may be conveniently supported from a wall or like surface.

15 A further object of the invention is to provide a hanger or support which will permit of the calendar being rolled, packed or shipped without interference therefrom, which is simple and inexpensive in construction and may be applied to the calendar when the latter is in process of formation, and which embodies a pin whereby the calendar may be directly fastened to a wall or suspended from a fastening member or 20 driven into the wall.

25 The invention consists of the features of construction, combination and arrangement of parts herein fully described and claimed, reference being had to the accompanying drawing in which:—

30 Figure 1 is a view of a calendar embodying my invention. Fig. 2 is a sectional view on an enlarged scale through the sheet clamping strip of the calendar and showing 35 the hanger in normal position. Fig. 3 is a view similar to Fig. 2 showing the pin arranged for direct engagement with a wall to support the calendar therefrom. Fig. 4 is a plan view of the blank from which the 40 hanger strip is made.

45 Referring to the drawing, 1 designates a calendar of the character usually hung upon a wall, the same comprising a single sheet or a series of sheets bound at their upper edge by a clamping strip 2. This strip, as shown in the present instance, comprises a piece of sheet metal folded to engage the upper edges of the sheet, which are folded the sheets are firmly and securely bound 50 together.

The hanger or support comprises a main

member 3, consisting of a thin strip of brass or other bendable or malleable metal. The lower end 4 of this strip is inserted between the last sheet of the tablet and the adjacent 55 fold of the binder strip 2, whereby the strip 3 is permanently fastened in place.

The upper end of the strip is provided with a portion 5, rolled into tubular form and receiving the stem 6 of a fastening device. This fastening device is in the form of a pin, the stem 6 of which is provided with a pointed end 7 and a hook-shaped end 8, forming a combined head or finger piece and suspending element. As shown in Fig. 65 4, the tubular portion 5 is formed partially from an offset projecting laterally from one side of the upper end of the blank from which the strip 3 is made. The stem 6 is formed with shoulders or stop members 9 70 by which it is held from endwise movement in the sleeve or tubular portion 5.

By reference to Figs. 1 and 2 it will be seen that normally the pin may be disposed vertically and substantially in the plane of 75 the body of the calendar, so that the calendar may be rolled, stored away in a flat condition, or packed or shipped with other pads without interference from the hanger, and without liability of injuring the latter. 80 In this position, the hooked end of the pin provides a means whereby the hanger may be engaged with a nail or other support to hang the calendar upon a wall. By reference to Fig. 3, it will be seen that by bending 85 the strip so as to dispose the sleeve and pin at right angles to the calendar, the pin may be forced into a wall or other support to hang the calendar without the aid of any other supporting means. A convenient and 90 always ready hanger is thus provided for use when a nail or other support is not at hand.

In embedding the pin in a wall it will of 95 upon themselves and with the strip, whereby course be understood that the hooked end of the pin serves as a head or finger piece whereby it may be manipulated.

I claim:—

A hanger or suspending device embodying 100 a bendable metal body formed to provide a main member, attaching means at one end

of said main member, a sleeve at the opposite end of said main member adapted to be disposed parallel with the plane of said body or at right angles thereto by bending the body at the point of intersection of the sleeve and main member, a stem projecting through said sleeve and pointed at one end and hooked at its opposite end, and stop members

on the stem engaging the ends of the sleeve to hold the stem from endwise displacement. 10

In testimony whereof I affix my signature in presence of two witnesses.

JOSEPH A. HAMMER.
